DESIGN FOR A CLOCK CASE

William P. Gallagher, Chicago, Ill., assignor to International Register Company, Chicago, Ill.,
a corporation of Illinois

Application November 5, 1945, Serial No. 123,476

Term of patent 7 years

(Cl. D42—7)

To all whom it may concern:

Be it known that I, William P. Gallagher, a citizen of the United States, residing at Chicago, in the county of Cook and State of Illinois, have invented a new, original, and ornamental Design for a Clock Case, of which the following is a specification, reference being had to the accompanying drawing, forming a part thereof.

In the drawing:

The figure is a front perspective view of a clock case showing my new design, the opposite side thereof presenting the same appearance as the side shown, and the back being plain.

I claim:

The ornamental design for a clock case, substantially as shown and described.

WILLIAM P. GALLAGHER.
